US00D608129S

(12) **United States Design Patent**
Spear et al.

(10) **Patent No.:** **US D608,129 S**
(45) **Date of Patent:** **** Jan. 19, 2010**

(54) **WATER COOLER**

(75) Inventors: **Gregory N Spear**, Los Angeles, CA (US); **Terry Havener**, Martinsville, IN (US); **Chun Yen Wang**, Ormond Beach, FL (US); **Hung Hsiang Chen**, Taipei (TW)

(73) Assignee: **MTN Products, Inc**, Pomona, CA (US)

(**) Term: **14 Years**

(21) Appl. No.: **29/304,897**

(22) Filed: **Mar. 10, 2008**

(51) **LOC (9) Cl. 07-01**

(52) **U.S. Cl. D7/306; D7/313; D7/311**

(58) **Field of Classification Search** D7/300, D7/304-311, 313, 312; 222/325, 185.1

See application file for complete search history.

Primary Examiner—Marianne Pandozzi

(74) *Attorney, Agent, or Firm*—Michael P. Mazza

(57) **CLAIM**

We claim the ornamental design for the water cooler, as shown and described in the drawings.

DESCRIPTION

FIG. 1 is a front, side, top perspective view of a water cooler showing our new design;

FIG. 2 is a front perspective view of the water cooler shown in FIG. 1;

FIG. 3 is a right side elevational view thereof;

FIG. 4 is a left side elevational view thereof;

FIG. 5 is a rear view thereof;

FIG. 6 is a top plan view thereof;

FIG. 7 is a bottom view of the water cooler shown in FIG. 1; and,

FIG. 8 is a front, side, top perspective view of a water cooler showing a second embodiment of our new design.

The broken lines in the drawings are included for the purpose of illustration and form no part of the claimed design.

1 Claim, 4 Drawing Sheets
